FUEL STOKER

Clark Scholl, Springfield, Ohio, assignor, by
mesne assignments, to The Steel Products En-
gineering Company, Springfield, Ohio, a corpo-
ration of Ohio

Application October 8, 1934, Serial No. 747,327

12 Claims. (Cl. 110—45)

The present invention relates to improvements in fuel stokers of the underfeed type, and more particularly to a novel method and means for preventing the escape of smoke and obnoxious gases to the surrounding atmosphere.

Underfeed stokers ordinarily comprise a fuel hopper, a burner adapted to be mounted in a closed combustion chamber and having an upwardly opening retort with tuyère openings adjacent the top and a plenum chamber about the retort and communicating with the tuyère openings, a duct connecting the hopper and the retort, conveyer means for feeding fuel through the duct toward the retort, an air duct connected to the plenum chamber, and means for supplying air under pressure to the air duct. The pressure of the air at the zone of combustion tends to force some smoke and products of distillation and combustion backwardly through the duct and hopper into the surrounding atmosphere. This is objectionable in that it reduces the efficiency of combustion, and results in an unclean and unhealthful condition which is particularly offensive in domestic installations.

It has been proposed heretofore to overcome the foregoing difficulty by introducing air under pressure from the air duct or the plenum chamber into the fuel duct. The air so introduced was intended to counterbalance the downward pressure in the retort. It has been found, however, that under many operating conditions, such counterbalancing of pressures effective to prevent objectionable back smoking and gassing is not obtained. Where the air is introduced through long or restricted passages, the pressure is likely to suffer a substantial drop before entering the duct to a point below that at the zone of combustion. Moreover, the air can reach the combustion chamber only by passing upwardly through the compact fuel bed which sets up a substantial resistance to flow, and hence still further decreases the counter-pressure. Since the fuel rarely fills the duct completely but defines an unrestricted air passage along the top to the hopper when a conveyer screw is employed, the resistance to upward flow tends to cause a substantial portion of the air with smoke and obnoxious gases to pass to the hopper. This is particularly true where certain kinds of cheap fuel are used.

The primary object of the present invention therefore resides in the use of a novel means for preventing back smoking and gassing by scavenging the fuel duct of smoke and obnoxious gases that may pass downwardly from the zone of combustion, and preferably returning such smoke and

gases to the combustion chamber without requiring them to pass through the fuel bed.

Another object resides in the provision of an underfeed stoker comprising new and improved means in the form of a relatively short and low resistance air flow passage from the source of pressure air through the upper portion of the fuel duct directly to the zone of combustion.

Further objects reside in the provision of a novel means in the form of a low resistance air flow passage including the duct for preventing back smoking and gassing which is efficient in operation, and simple, compact and inexpensive in construction.

Other objects and advantages will become apparent as the description proceeds.

In the accompanying drawings, Figure 1 is a plan view of a stoker embodying the features of my invention.

Fig. 2 is a fragmentary plan view on an enlarged scale of the base section of the burner.

Fig. 3 is a longitudinal vertical sectional view taken along line 3—3 of Fig. 2, but with tuyère blocks mounted on the burner base section.

Fig. 4 is an elevational view of the inlet end of the burner.

Figs. 5 and 6 are fragmentary transverse sectional views taken respectively along lines 5—5 and 6—6 of Fig. 2.

Fig. 7 is a fragmentary sectional view taken in the plane of Fig. 3, but illustrating a modified form of the invention.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

Referring more particularly to the drawings, the stoker constituting the preferred embodiment of the invention comprises an upright fuel hopper 10, an underfeed burner 11, a fuel duct 12 connecting the base of the hopper to the burner, a screw conveyer 13 extending from the hopper into the duct for feeding fuel to the burner, and power drive means 13^a for rotating the conveyer.

The burner 11 may be provided in various forms, and is herein shown as comprising a base section 14 generally rectangular in form and adapted to be mounted on a suitable support 55

(not shown). The base section 14 has an upright wall 15 and top and bottom walls 16 and 17. Formed integral with the base section 14 is a retort 18 opening upwardly through the central portion of the wall 16 and having a horizontal cylindrical inlet duct or passage 19 opening through the wall 15 at the front end of the burner 11.

Formed on the exterior of the wall 15 in axial alignment with the duct 19 is a mounting ring 20 snugly receiving the discharge end of the duct 12. A semi-cylindrical bracket 21 with marginal side flanges 22 is formed integral with the upper portion of the ring 20, and constitutes an axial extension thereof. The fuel duct 12 is securely clamped in position between the bracket 21 and an underlying semi-cylindrical plate 23 abutting against the end of the ring 20 and having marginal side flanges 24 bolted to the flanges 22. A pin 25 extends vertically through the bottom of the plate 23 into a hole 26 in the duct 12 to hold the latter against rotation.

The base section 14 defines a plenum chamber 27 about the retort 18. A blower 28, mounted in fixed relation to the hopper 10 and operatively connected to the drive means 13^a, discharges through an air duct 29 to the chamber 27.

Mounted on the top wall 16 of the base section 14 and about the upper edge of the retort 18 to 30 constitute a vertical continuation thereof are a plurality of closely abutting tuyère blocks 30 and two front tuyère blocks 30^a. The blocks 30 when assembled define an air chamber 31 communicating through openings 32 in the bottom walls of 35 the blocks and registering openings 33 in the top wall 16 with the plenum chamber 27, and discharging through tuyère openings 34 to the space immediately above the retort 18.

In operation, fuel from the hopper 10 is fed 40 through the duct 12 into the retort 18 in which it is forced upwardly to form the fuel bed. Air under pressure from the chamber 27 is discharged through the openings 33 and 32, the chamber 31 and the tuyère openings 34 into the top of the 45 bed to support combustion. As combustion occurs, the pressure created at the zone of combustion by the pressure of the air tends to force some of the products of combustion and the products of initial distillation obtained in the lower portion of the retort 18 into the fuel duct 12.

The primary feature of the present invention resides in effectively preventing such products from passing backwardly to the hopper 10, and more particularly in removing them from the tube 12. The means employed for this purpose 55 serves to effect the flow of a constant stream of air under pressure through the discharge end of the duct 12 and then outwardly along a path of low resistance. Any smoke or obnoxious gases 60 entering the duct 12 become entrained in the air and are therefore removed before they can reach the hopper 10. In addition, the air introduced into the duct 12 sets up a pressure in opposition to the back pressure in the retort 18, 65 and to the extent that this is effective serves to reduce the amount of the objectionable products to be removed.

In the present instance, the means for preventing back smoking and gassing comprises an 70 external hollow T-shaped enlargement 35 formed on the top of the bracket 21 and defining a similarly shaped air passage 36. The lateral ends of the passage 36 are connected respectively through openings 37 in the wall 15 to the plenum chamber 27. The longitudinal end of the pas-

sage 36 discharges laterally through an opening 38 to the inner surface of the bracket 21. Two parallel longitudinal slots 39 are formed in and open through the top portion of the duct 12, and are in registration with the opening 38 to complete the air passage connection between the plenum chamber 27 and the duct. 5

The two front tuyère blocks 30, adjacent the inlet end of the burner 11, define an air chamber 40 with a tuyère opening 41 and out of direct 10 communication with the plenum chamber 27. These blocks rest on a connecting portion 42 of the top wall 16 between the wall 15 and the retort 18. Two depending T-shaped lugs 44 on the front tuyère blocks 30 fit respectively in notches 15 45 in opposite sides of the wall portion 42, and the heads of the lugs hook under the marginal edges thereof. Two parallel spaced vertical walls 46 extending downwardly from the wall portion 42 to the duct 19 between the wall 15 and the retort 20 18 define with these parts an air chamber 47 which communicates at the top through an opening 48 in the wall portion 42 with the chamber 40 and through an opening 49 in the front wall 25 of the retort 18 with the interior of the latter 25 adjacent the top of the duct 19. Extending downwardly and forwardly in the chamber 47 from the upper edge of the retort 18 partially across the opening 49 is an inclined baffle wall 50.

During the operation of the stoker, air under 30 pressure from the plenum chamber 27 passes through the openings 37, the passage 36, the opening 38 and the slots 39 into the upper portion of the discharge duct 12. The connection is comparatively short and substantially unre- 35 stricted, and hence the pressure of the air entering the duct 12 is practically the same as that of the air entering the fuel bed at the zone of combustion through the tuyère openings 34. The pressure in the duct 12 opposes the downward 40 air pressure in the retort 18, and therefore tends to reduce the quantity of smoke and gases that may seek an outlet through the hopper 10. The air passes over the fuel between the slots 39 and the discharge end of the duct 12 and duct 19, 45 through the opening 49, and across the baffle wall 50 into the chamber 47, and then through the opening 48, the chamber 40 and the tuyère opening 41 into the fuel bed at the zone of combustion. Thus, the air flows in contact with the 50 fuel along a short path of comparatively low resistance. Unless the stoker is operating at full load, there is likely to be an air space in the top of the duct 12 adjacent its discharge end. In this case, a part of the air introduced through 55 the slots 39 will flow through this unrestricted opening and out through the opening 49. However, the direct connection between the plenum chamber 27 and the duct 12 by way of the passage 36 will provide for the flow of a sufficient volume 60 of air to permeate the mass of fuel in the lower part of the duct and effectively prevent smoke and gases from passing back through the duct to the hopper 10. The air is not obliged to pass through the relatively large mass of fuel in the 65 fire bed but takes the path of lower resistance through the openings 49 and 41. The air will not flow backwardly through the loaded hopper 12 since the above described path is the one of least resistance. Thus, there will be a current 70 of air flowing through the duct 12 in a direction away from the hopper 10, and this current of air will entrain any smoke or obnoxious gases that may be present. As a result, back smoking and gassing is effectively prevented. 75

In the modified form shown in Fig. 7, the duct 19^a extends externally of the vertical wall of the base section and is formed with a long counterbore 52 receiving the discharge end of the duct 12^a. The base section is formed with an air chamber 53 which communicates upwardly through an opening 54 in the wall 16^a with the interior of the tuyère structure and downwardly through an opening 55 with the interior of the duct 19^a. A slot 56, formed in the top of the duct 12^a and inclined downwardly and rearwardly, registers with the opening 55 to complete the air flow connection between the plenum chamber 27^a and the duct. A discharge pipe 57, connected to the duct 19^a, communicates, through notches 58 and 59 formed respectively in the end of the duct 12^a and the shoulder defined by the counterbore 52, with the retort 18^a, and extends upwardly through the chamber 53, the opening 54 and the tuyère structure. The pipe 57 may lead to any suitable place of disposal for the air and entrained products entering from the duct 12^a, and is herein shown as discharging through one of the tuyère openings 34^a to the zone of combustion. The operation is similar to that of the form illustrated in Figs. 1 to 6.

I claim as my invention:

1. A stoker comprising, in combination, an underfeed burner having a retort, a tuyère structure on said retort, and a plenum chamber about said retort and communicating with said tuyère structure, a hopper, a horizontal duct connecting said hopper to said retort, a conveyer for advancing fuel from said hopper through said duct into said retort, means for supplying air under pressure to said plenum chamber, a semi-cylindrical bracket on said burner and engaging the upper portion of the discharge end of said duct, a complementary semi-cylindrical plate removably secured to said bracket and engaging the underside of said duct, a longitudinal slot formed in the top and opening through the wall of said duct, an air flow passage formed in said bracket and communicating at spaced points with said plenum chamber and communicating through said slot with the interior of said duct, means defining an auxiliary tuyère chamber out of direct communication with said plenum chamber, and having an inlet opening from said retort adjacent the upper portion of the discharge end of said duct, and a downwardly inclined depending baffle in said auxiliary chamber extending across said inlet.

2. A stoker comprising, in combination, an underfeed burner having a retort, a tuyère structure on said retort and a plenum chamber about said retort and communicating with said tuyère structure, a hopper, a horizontal duct connecting said hopper to said retort, a conveyer for advancing fuel from said hopper through said duct into said retort, means for supplying air under pressure to said plenum chamber, a bracket on said burner and engaging the upper portion of the discharge end of said duct, means for securing said duct in position against the underside of said bracket, an opening in the top wall of said duct, an air flow passage formed in said bracket and communicating with said plenum chamber and through said opening with the interior of said duct, and means defining an auxiliary tuyère chamber out of direct communication with said plenum chamber, and having an inlet opening from said retort adjacent the upper portion of the discharge end of said duct.

3. In a stoker, in combination, a burner having an underfeed retort and a tuyère structure on

said retort and including a tuyère chamber and an auxiliary tuyère chamber, a fuel duct discharging into the bottom of said retort, means for supplying air under pressure to said duct, and means providing an air passage connecting the interior of said retort to said auxiliary tuyère chamber and utilizing the pressure of the air supplied to said duct for returning gases from said duct and from the lower portion of the retort through the tuyère structure to the upper portion of the retort.

4. In a stoker, in combination, a burner having an underfeed retort and including a tuyère chamber and an auxiliary tuyère chamber, a fuel duct discharging into the bottom of said retort, means for supplying air under pressure to said duct, and means providing an air passage connecting the interior of said retort adjacent the discharge end of said duct to said auxiliary tuyère chamber and utilizing the pressure of the air supplied to said duct for returning gases from said duct and from the lower portion of the retort through the tuyère structure to the upper portion of the retort.

5. In a stoker, in combination, a burner having an upwardly opening underfeed retort with a horizontal fuel inlet duct, and a tuyère structure on said retort having a tuyère chamber and an auxiliary tuyère chamber out of direct communication with said tuyère chamber, a fuel duct discharging into said inlet duct, means for supplying air under pressure to the upper portion of the discharge end of said fuel duct, and means providing an air passage and utilizing the pressure of the air supplied to said fuel duct for returning gases from said fuel duct and from the lower portion of said retort through said tuyère structure to the upper portion of said retort, said air passage connecting the interior of said retort adjacent the point of juncture with the top of said inlet duct directly to said auxiliary tuyère chamber.

6. In a stoker, in combination, a burner having an underfeed retort with a horizontal inlet duct, means for supplying fuel to said duct, means for supplying air under pressure through said duct into said retort, and means forming an air outlet from said retort at a point adjacent the outlet of said duct and utilizing the pressure of the air supplied through said duct to said retort for scavenging gases from the lower portion of the retort.

7. In a stoker, in combination, a burner having an upwardly opening underfeed retort, means for supplying fuel to the bottom of said retort, means for admitting air under pressure to the lower portion of said retort, means for withdrawing air and gases from the lower portion of said retort, and means including a by-pass located outside said retort for returning said air and gases to the upper portion of said burner.

8. In a stoker, in combination, a burner having an upwardly opening underfeed retort, means for supplying fuel to the bottom of said retort, a tuyère structure on said retort, means for admitting air under pressure to the lower portion of said retort, and means for withdrawing air from the lower portion of said retort and directing same to said tuyère structure to be discharged into the top of said burner.

9. In a stoker, in combination, a burner having an upwardly opening underfeed retort, means for supplying fuel to the bottom of said retort, a tuyère structure on said retort and having a discharge opening, means for admitting air under

pressure to the lower portion of said retort, and a pipe opening from the lower portion of said retort, and discharging to said discharge opening of said tuyère structure.

- 5 10. A stoker comprising, in combination, an underfeed burner having a retort with a horizontal inlet duct, a main tuyère structure, an auxiliary tuyère structure, said structures being disposed on said retort, and a plenum chamber 10 about said retort and communicating with said main tuyère structure, a hopper, a horizontal fuel duct connecting said hopper to said inlet duct, a conveyer for advancing fuel from said hopper through said ducts into said retort, means for 15 supplying air under pressure to said plenum chamber, a bracket on said burner and engaging the upper portion of the discharge end of said fuel duct, a plate removably secured to said bracket and engaging the underside of said fuel duct, 20 a slot formed in the top of said fuel duct, an air flow passage formed in said bracket and connected to said plenum chamber and through said slot with the interior of said fuel duct, an opening formed in said retort below said main tuyère 25 structure and communicating through a passage directly with said auxiliary tuyère structure.

11. A stoker comprising, in combination, an

underfeed burner having an upwardly opening retort, a tuyère structure mounted on the top of said retort and coacting with said retort to define a fire pot, means for supplying air under pressure to said tuyère structure, a substantially horizontal fuel supply duct means opening to the bottom of said retort and formed in the top with longitudinally spaced air inlet and outlet openings, a passage connecting said air supply means to said inlet opening, and a passage for conducting gases away from said outlet opening. 5

12. A stoker comprising, in combination, an underfeed burner having an upwardly opening retort, a tuyère structure mounted on the top of said retort and coacting with said retort to define a fire pot, means for supplying air under pressure to said tuyère structure, a substantially horizontal fuel supply duct means opening to the bottom of said retort and formed in the top with an air inlet opening spaced from said fire pot and 15 an air outlet opening at the lower portion of said fire pot, a passage connecting said air supply means to said inlet opening and a passage formed in part by said tuyère structure for directing air and gases from said outlet opening to the top of 20 said fire pot. 25

CLARK SCHOLL.
